UNITED STATES PATENT OFFICE.

JOHN M. TEETOR, OF INDIANAPOLIS, INDIANA, ASSIGNOR OF ONE-HALF TO
CHARLES R. BALKE, OF INDIANAPOLIS, INDIANA.

TENPIN.

No. 846,164.

Specification of Letters Patent.

Patented March 5, 1907.

Application filed May 31, 1906. Serial No. 319,539.

To all whom it may concern:

Be it known that I, JOHN M. TEETOR, a citizen of the United States, residing at Indianapolis, in the county of Marion and State of Indiana, have invented certain new and useful Improvements in Tenpins, of which the following is a specification, reference being had therein to the accompanying drawing.

10 My invention relates to improvements in tenpins, and will be hereinafter more fully set forth.

The object of this improvement is to provide a tenpin of such material and construction as not to be capable of being battered out of shape or chipped, and thereby destroy the contour of the pin; also, to provide a retractive or yielding shield or a deadening-armor backed by a suitable cushion or resili-
20 ent bed or liner, whereby the force of the blow of a ball against said shield will be in a measure absorbed and the said shield will assume its original form. I attain these ob-
25 jects by means of the tenpin illustrated in the accompanying drawings, in which simi-
lar numerals of reference designate like parts throughout the several views.

Figure 1 is a broken part-sectional side ele-
30 vational view of my invention of an im-
proved tenpin; and Fig. 2 is a sectional plan
view of the tenpin, taken through the line A
B. (See Fig. 1.)

The body of 1 the tenpin is usually of a hard wood, such as maple, turned to the regular universal and standard form and size. The strike portion of the tenpin 1 is provided with a wide flat groove 2, which encircles the pin 1 at this portion and divides said pin 1 into an upper or handle portion 3 and a lower or base portion 4, which portions of said ten-
35 pin are connected by their integral neck portion 5. I next provide a band 6, of rubber of the required elasticity or other resilient ma-
terial of suitable thickness and width or of a
40 thickness sufficient when closely wrapped
round said neck 5 one turn to half fill the
groove, into which half-filled portion of said
groove 2 is fitted the outer shield or pad 7. I
45 next cement the said elastic bed or pad 6 to
50 the said neck 5 to permanently secure it in

said groove 5. I next procure sole-leather of the proper width, thickness, and toughness and fit the same in said groove to completely encircle or surround the yielding or resilient pad or bed 6 and completely fill the said 55 groove 5 to form an outer shield or protecting-armor 7. The outer shield 7 thus formed is now cemented to said resilient or elastic bed or pad 6 to be permanently secured in position in said groove 5 and be maintained in 60 close contact with said resilient bed. The tenpin is now centered in a suitable turning-
lathe, and the leather shield 7 and the exte-
rior surface of the tenpin are truly turned to the required form, so as to present a smooth 65 even surface of regular outline.

Referring to Fig. 2, it will be noted that the backing is in close contact with the neck 5. The resiliency of the pad 6 is dependent on the elasticity of the material or rubber of 70 which it is made and is sufficient to restore the shape or outline of the shield of the ten-
pin to conform with the remaining uncovered or unprotected portions of the said tenpin. A base-ring 8 is now cemented to the base of 75 the tenpin for the purpose of not only protect-
ing the edge thereof and preventing a chip-
ping of the wood at that portion of the ten-
pin; but also to form a bearing-ring which
will be readily adjusted to an uneven surface 80
to support the said tenpin in a vertical posi-
tion.

I claim—

1. The combination with a tenpin, of an inlaid deadening or yielding pad or shield 85 situated at and surrounding the striking por-
tion of said tenpin and a cushion-pad situ-
ated between said shield or yielding pad and the unyielding portion of said tenpin.
2. The combination with a tenpin provided 90 with a central shield-receiving groove of a yielding or retractive shield or pad and a re-
inforcing-backing of a resilient material.

In testimony whereof I affix my signature in presence of two witnesses.

JOHN M. TEETOR.
